PRINTING OF FIBROUS MATERIALS BY
IMPREGNATIONMelvin R. Greiser, Cincinnati, Ohio, assignors to
Carthage Mills Incorporated, Carthage, Ohio,
a corporation of Ohio

Application June 7, 1933, Serial No. 674,723

2 Claims. (Cl. 8—5)

My invention relates to the printing of fibrous materials, pile fabrics and the like. In the manufacture of carpeting and other pile fabrics it has been the general practice to produce designs by weaving the material initially from yarns or threads of differing colors. It has been realized that fabrics might be more cheaply made were it possible to produce the desired designs in them by a printing process employing dyes, 5 after fabrication. More or less successful attempts have been made to print upon pile fabrics or fibrous materials by mixing dyes and mordants, together with certain materials to give body to the mixture, and then using the mixture 10 in place of ink in a printing process. Difficulties have been met with, however, which in general have to do with the penetration of the color, the fixing of the color upon or into the fibers, adequate printing mechanism in view of the difficulty of handling dye combinations and corrosive mordants, mechanical difficulties in printing, such as the collection of lint by the plates, 15 etc.

The primary object of my invention is to provide an adequate, cheap and simple process for printing by impregnation, pile fabrics or fibrous bodies. I shall describe my invention in connection with the manufacture of a relatively inexpensive floor covering by a printing process 20 from a non-woven fibrous body material, as will hereinafter be described in detail, it being understood, however, that my invention is by no means confined to any particular character of fabric, woven or unwoven, upon which printing is desired. If it is my object, however, to produce the said inexpensive floor covering, it will be obvious that considerations of economy in process 25 and apparatus become very important. Consequently it is a more specific object of my invention to provide a simplified general process for the purpose desired. It is also my object to provide a process in which, for the printing step, ordinary printing means such as have heretofore been employed in the felt base floor covering 30 art, may be utilized without deterioration. It is also my object to make provision for a better penetration of the color, for the protection of the printing plates and general apparatus, and for taking care of the necessary supplementary operations, such as steaming the web.

These and other objects of my invention which will be set forth hereinafter or will be apparent to one skilled in the art upon reading these specifications, I accomplish by that certain series 35 of manipulations and by that construction and

arrangement of parts of which I shall now set forth the aforesaid exemplary embodiment. Reference is made to the drawing, wherein:—

Figure 1 is a semi-diagrammatic view of a printing machine arranged in accordance with 5 my invention to carry out my process.

Fig. 2 is a representation of a web of material treated by my process.

Fig. 3 is a sectional view of a steaming device.

As aforesaid, I shall describe my invention in 10 connection with the printing of a relatively inexpensive non-woven, felted mass or pad of fibers. Such materials are now obtainable on the market in wide widths. They are made up of a relatively loosely felted mass of fibers, for the most part 15 animal fibers. One face of the web is usually treated with such a substance as rubber latex, which contributes some strength to the web, and also gives it non-slipping characteristics when used as a rug. While my invention is not limited 20 to any particular material to be printed upon, the material referred to is relatively inexpensive and is suitable for the manufacture of rugs which are both durable and beautiful, and which are exceedingly economical providing the problems 25 connected with the treating of the same are solved.

Hitherto such problems have been baffling. An attempt has been made to mix a mordant, such as formic acid, with suitable dyes and gums to 30 give body to the composition, and then print therewith upon the web. But inadequate penetration has been secured, the printing plates soon pick up lint or dust from the web and become fouled so that the printing is no longer 35 cleanly done; and the acid mordants are corrosive in their character and attack the printing plates if they are of metal, and in any event attack the machinery bearing the printing plates. The steaming has had to be done in large chambers or ovens, and where intermediate steamings are necessary the process has had to be interrupted. Attempts have been made to steam the 40 web by blowing live steam thereon from a plurality of nozzles; but this is both wasteful of 45 steam and creates unpleasant working conditions. Additionally, unless the steam is specially produced, it is likely to contain oil or grease and foreign materials, which tend to soil the web. The admission of live steam to steaming chambers 50 is subject to the same disadvantages, though to somewhat lesser degree. In addition, washings and dryings of the web, where necessary, have greatly slowed up the process; and these factors have in general made the printing of webs of the 55

These and other objects of my invention which will be set forth hereinafter or will be apparent to one skilled in the art upon reading these specifications, I accomplish by that certain series 35 of manipulations and by that construction and

character described an operation out of all proportion as to costliness to the cost of the web itself.

I have found that by my process, webs of the character described, or pile fabrics, etc. may be adequately printed upon the ordinary flat bed printing press used in the manufacture of felt base floor coverings. It should be understood that my invention is not limited to use upon flat bed printing presses, but that the principles may be applied and practiced upon other types of printing machinery, such as the rotary presses and the like; and I desire the appended claims to be understood as not limited to the general features of any particular character of printing mechanism, excepting where specifically set forth.

I have found that by the application of the mordant and penetrant or wetting agent first to the web, I secure a number of remarkable advantages. In the first place, the mordant handling equipment is localized at one point and is reduced to a minimum. Within the limits of sound economy it can be such equipment as is not affected by the corrosive character of the mordant, or if not, can be replaced from time to time, as necessary, without great cost. Secondly, the remainder of the printing machine, including the printing plates and moving parts are protected from the action of the mordant and do not tend to be corroded thereby. In the third place, the wetted character of the web, I have found, entirely prevents the printing plates from picking up and becoming fouled by dust, lint, fibers etc. from the web. In the fourth place, when the web is wetted without being entirely saturated by the mordant, the penetration of colors into the web is much more effective. The dye substance employed appears to strike downwardly through the web, penetrating substantially throughout its depth without undesirable side spreading of the color. In the fifth place, my printing mechanism handles nothing but the dye substance, together with such gums or other materials as may be thought necessary to give the dye sufficient body. This appears not only to give me a more advantageous substance for color application, but also appears to make for greater permanence in the web. In the sixth place, the character of operations performed by me are exceedingly simple, and where desired, may be repeated as often as necessary. Thus the web may be mordanted and printed, and afterward mordanted again. Printings may follow mordatings as often as desired, and double printings may be employed.

Again I have devised a method and means for steaming the web. In general these means are analogous to the printing means in that they contact the sheet or web intermittently, as in the flat bed press, or by a rolling contact as in the rotary press. They are in the nature of pressing and steaming devices in which the steam escapes to the web through confining means which not only permit steaming at a higher temperature, but localize the action of the steam and filter out of the steam such foreign substances as might otherwise stain or soil the web.

I have illustrated my invention in Fig. 1 as applied to a flat bed printing press of the type generally used for the paint printing of felt base floor coverings. The press is an elongated structure built upon a frame 1, having a table 2. The sheet 3 is carried over this table from a source of supply 4, by means of the ordinary chain carrying device having points to penetrate the web,

or otherwise as desired. Upon the framework there are mounted a series of reciprocating standard devices 5, controlled by cams 6. The standards 5 bear the printing blocks or plates 7. As the cams 6 rotate in timed relationship, the standards 5 are caused to pull the plates 7 down into contact with the web during periods of rest thereof, and to raise them out of contact with the plate during the inking operation, and during the movement of the web. The web of course moves in a step by step manner through the printing device. Inking pans 8 to contain the color are provided. These pans contain suitable application devices, not shown, but usually in the nature of rolls with doctors, and they are mounted to reciprocate longitudinally of the machine. For this purpose small wheels on the pans engage tracks along the edges of the machine, and mechanism is provided to move the pans in synchronism with the other movements of the machine so that when the printing plates are raised, the pans pass beneath them and apply color to the printing surfaces, all as is understood in this art.

An exemplary printing machine of this character contains 30 or more of the standards 5, which will be found adequate for the carrying on of my invention.

I have shown a web 3 coming from a supply roll onto the table 2. As an initial operation I apply the mordant to the web. For this purpose I have shown a series of nozzles 9, located above the table from which the mordant is sprayed onto the web. I prefer this method of application because it is one of the simplest and least expensive which I may use, but other methods of application are suitable. I may apply the mordant by means of felt-covered blocks, or by means of a roll, which may be of rubber or other acid resistant substance. Under some circumstances I can knife the mordant onto the web; but I do not ordinarily prefer to do this, since while I desire my web to be thoroughly wetted, I do not desire it to be completely saturated. Consequently spray coating or roll coating is preferable, in my opinion, either to knifing or to passing the web bodily beneath the surface of a bath of mordant, which, however, might be done.

Next it is usually advantageous to steam the web after mordanting to soften the fibers and increase the penetration thereof by mordanting. I have shown two of the standards marked 5a, as bearing steaming devices indicated generally at 10. These devices have connections 11, with a source of live steam which may, of course, be either the general steam supply of the plant or a special source. Steaming devices will in general be more or less of the same proportions as the printing plates with reference to their area, but it is obvious that they may be larger or smaller, as desired, and more particularly that more than an oppositely disposed pair of standard members 5a may be employed to control a single steaming device.

I have illustrated in Fig. 3 a sectional view of an exemplary steaming device. It comprises a top member 12, having passageways 13 for steam and having the connection 11. Beneath the head I usually prefer to provide pads of fibrous material indicated at 14. These give resiliency to the steaming device, and also act as filters to remove from the steam foreign materials therein. A general, pervious covering 15 is provided to cover the under surface of the steaming device. I have shown at 16 diagram-

matically a two-way valve which may be understood as either manually controlled or controlled in synchronism with the operation of the printing machine by a suitable cam arrangement. 5 This valve is connected by means 17 to a source of steam, and by means 18 either to a vacuum pump, or to a source of air under pressure. When the valve mechanism is moved to the left, steam is admitted to the steaming device. When 10 it is moved to the right, the steam is cut off and connection is made to the vacuum pump or source of air. Vacuum is preferable because it tends more effectively to remove the steam. When the valve is in neutral position no fluid 15 pressure is applied to the steaming device. The general sequence of operations will be a lowering of the steaming device against the web under pressure, the application of steam thereto for a predetermined interval, the cutting off of the 20 steam and the application of vacuum thereto, and finally the raising of the steaming head.

Having thus been steamed, the web 3 passes beneath the printing heads 7 on the standards 5 and is printed in much the same manner as 25 the printing operations heretofore carried on on felt base floor coverings. The pans contain suitable dyes, together with body-giving gums. The previous application of mordant to the web increases the penetrative power of the dyes so applied. The pre-treatment of the fibers with the mordant increases the fastness of the colors produced, whereas the previous steaming of the web also appears to assist the penetration of the 30 fibers by the dyes.

35 In some instances double printing operations will be found desirable. Thus a plurality of the printing plates 1 may be employed to print one color, or the cam arrangement which controls the travel of the web may be so adjusted 40 that two or more printing operations by the same plate are performed upon the same portion of the web.

Intermediate the printing operations if desired, another mordant application may be made as 45 by means of the nozzles 9a, and the web may again be steamed by heads 10a.

Additional printings may be carried on as by blocks 1a, and a final steaming applied, as by heads 10b.

50 It should be pointed out that the nature of the steaming devices employed by me permits a much more effective steaming of the web. By reason of the close contact of the steaming device to the web, not only may the steaming 55 be carried on under considerable pressure, but also for that reason at an elevated temperature. The purpose of the gum in the dye, as aforesaid, is to give it suitable body for printing. An excess of gum or poorly distributed gum is not desirable in the web. If a printed web is treated with steam merely by blowing the steam upon it there

is a tendency of the gum to segregate toward the top of the sheet, giving an undesirable surface texture. On the contrary, in my process there is a tendency for the gum and wetting agent to penetrate the web and, so far as it 5 segregates, to segregate at or near the bottom of the web, where it increases the permanency of the web, leaving the upper dyed fibers clear and brilliant.

10 Since my printing plates do not have to carry mordant, I may, if desired, use metal printing plates, though wooden plates are in general preferable and more economical. In any event, the machinery is protected from the mordant, and the plates show no tendency to pick up lint and 15 foreign matter.

After a final steaming, the web may either be finished, or if a washing is desired, it may be carried through a washing pan 19 and finally steamed to dry it by one or more steaming heads 10c, on standards 5c. At the conclusion of these 20 operations, the web is finished and may be rolled up for sale or cut into a series of rugs, where the printing operation has produced rug borders. Since a final steaming may be employed to dry 25 the web, I do not need to provide either steam rooms or drying chambers, and in one operation I have produced a completed web.

It will be clear that modifications may be made 30 in my invention without departing from the spirit thereof, and in particular that my process may be carried on on other printing devices than that specifically illustrated herein. The finished web I have illustrated in Fig. 2, where 35 color applications 20 and 21 are shown as extending throughout the body of the fabric, the latex bonding coating being shown at 22. An increase in the intensity of the color shading toward the bottom of the web indicates a concentration of the gum at that point.

Having thus described my invention, what I 40 claim as new and desire to secure by Letters Patent, is:—

1. In a process of printing floor covering materials having a deep fibrous body, by impregnation, the steps of treating a fibrous web at one station with a mordant liquid to the extent of wetting said web generally, moving said web to another station and treating said web while wet with said mordant, with a selective color application without mordant.

2. A process of printing webs of floor covering materials having a deep fibrous body, by impregnation, which comprises applying a mordant without dye to said web generally at one stage, 55 passing said web to a second stage and steaming it, and passing said web to a third stage without drying and selectively applying dye without mordant to said wet web.

60 MELVIN R. GREISER.
